US0D1097164S

(12) **United States Design Patent** (10) **Patent No.:** **US D1,097,164 S**
(45) **Date of Patent:** **** Oct. 7, 2025**

(54) **MEDICAL DEVICE**

(71) Applicant: **ViOptix, Inc.**, Newark, CA (US)

(72) Inventors: **Kate LeeAnn Bechtel**, Pleasant Hill, CA (US); **Sophia Elizabeth Berger**, Palo Alto, CA (US)

(73) Assignee: **ViOptix, Inc.**, Newark, CA (US)

(**) Term: **15 Years**

(21) Appl. No.: **29/944,499**

(22) Filed: **May 28, 2024**

Related U.S. Application Data

(60) Continuation of application No. 29/717,295, filed on Dec. 16, 2019, now Pat. No. Des. 1,029,274, which is a continuation-in-part of application No. 29/641,081, filed on Mar. 19, 2018, now Pat. No. Des. 870,294, which is a division of application No. 29/561,749, filed on Apr. 19, 2016, now Pat. No. Des. 813,400.

(57) **CLAIM**

The ornamental design for a medical device as shown and described.

DESCRIPTION

FIG. 1 shows a perspective view of a design for a medical device.

FIG. 2 shows a front view of the medical device.

FIG. 3 shows a back view of the medical device.

FIG. 4 shows a left side view of the medical device.

FIG. 5 shows a right side view of the medical device.

FIG. 6 shows a top view of the medical device.

FIG. 7 shows a bottom view of the medical device.

FIG. 8 shows a view of the medical device being gripped by a hand of a user.

FIG. 9 shows a perspective view of a second embodiment of a design for a medical device.

FIG. 10 shows a front view of the second embodiment.

FIG. 11 shows a back view of the second embodiment.

FIG. 12 shows a left side view of the second embodiment.

FIG. 13 shows a right side view of the second embodiment.

FIG. 14 shows a top view of the second embodiment.

FIG. 15 shows a bottom view of the second embodiment; and,

FIG. 16 shows a view of the second embodiment being gripped by a hand of a user.

The dashed broken line showing of a user's hand in FIG. 8 depicts environmental subject matter and forms no part of the claimed design. All other dashed broken lines in the drawings depict portions of the medical device that form no part of the claimed design. The dot-dash broken lines depict the bounds of the claimed design and form no part of the claimed design.

1 Claim, 16 Drawing Sheets
